INVENTION

By *Ottis Nease*

his ATTORNEY.

UNITED STATES PATENT OFFICE.

EMILE CHRISTIAN PÉNIN, OF JOINVILLE-LE-PONT, FRANCE, ASSIGNOR TO PATHÉ CINÉMA, ANCIENS ÉTABLISSEMENTS PATHÉ FRERES, OF PARIS, FRANCE.

ELECTRIC CONTACT PLUG.

Application filed November 8, 1924, Serial No. 748,563, and in France December 1, 1923.

For certain uses it may be necessary to connect to a given contact plug an electric lamp, or other device employing the current, and on the other hand an electric motor. This is chiefly the case with installations for screen projection by the use of domestic or toy motion picture apparatus in which an electric lamp constitutes the source of light and an electric motor is used for actuating the cinematographic mechanism.

The object of the present invention is to provide an electric contact plug which may be interposed between the two elements of a plug and socket device, known per se, and by means of which the current from a single line may be supplied to two different apparatus, and which comprises also an electric resistance for varying the current in one of the said apparatus, whereby, in case the latter apparatus is an electric motor, its speed can be readily varied.

In the appended drawing which shows by way of example an embodiment of the said invention:

25 Fig. 1 is an elevation, with the outer wall of the plug broken away.

Fig. 2 is a horizontal section on the line A—A (Fig. 1).

30 Fig. 3 is an outer view of the plug interposed between the two elements, plug and socket, of a plug and socket connection of the known type which is shown diagrammatically as pertaining to a toy motion picture apparatus.

35 The construction illustrated in the drawing shows that the device according to the invention comprises two pins 1 and 2 and two sockets 3 and 4. On the other hand the motion picture apparatus is provided with two pins 16 adapted to fit in the sockets of the female part 15 of a usual plug and socket connection. The two pins 1 and 2 are also adapted to fit in said part 15 while the pins 16 may be introduced into the sockets 3 and 4.

The pin 1 is electrically connected to the socket 3, and the pin 2 is connected in like manner to the socket 4.

40 The electric current is supplied by the conducting wires connected to the member 15, and proceeds thence through the sockets 3 and 4 and the pins 16 to a lamp or other electric device, and through resistances 11

and the wires 5 and 6 to a motor or other apparatus. 55

The wire 5 is connected by the screw 7 to the pin 1 and to the socket 3, whilst the wire 6 is connected by the screw 8 to the conducting rod 9 on which a slide 10 may be shifted; said slide is provided with a strip 10^a in contact with the studs 11^a of the resistances 11.

The said resistances consist of coils of resistance wire which are connected to the respective studs 11^a. The last stud 13^a is connected by the screw 12 to the pin 2 and socket 4. The stud 13 forms an insulated contact piece which serves to break the current. A casing 14 covers the whole device. 65

The operation of the said device is as follows: 70

If it is desired to supply an electric motor by a circuit upon which one or more lamps, or a suitable apparatus, are already connected by means of a plug and socket 75 connection, the motor is connected to the two conductors 5 and 6 of the plug according to the invention, and the said plug is mounted between the elements 15 and 16 of the said plug and socket connection. For this purpose the pins 16 of the plug and socket connection are inserted respectively into the sockets 3—4 and the pins 1 and 2 are inserted into the sockets of the part 15; it will be observed that the circuit of the first apparatus (or lamp) connected to the line is not broken, since the pins 1 and 2 are respectively connected to the sockets 3 and 4. 80

85 As concerns the circuit of the motor which is connected to the wires 5 and 6, this circuit is connected to the line at 7 and 12, the variable resistance 11 being in series with the wire 6. The speed of the motor can thus be regulated by moving the slide over the contact studs 11^a. 90

95 Obviously, the plug according to the invention may be used for connecting to the supply circuit, other apparatus than electric motors.

Having now described my invention, what I claim as new and desire to secure by Letters Patent is:

1. An electric contact plug comprising an insulating base, two pins and two sockets mounted on said base and adapted to co-operate with the pins and sockets of a usual 105

plug and socket connection, each pin being electrically connected to one socket so as to form two sets, each of which comprising one pin and one socket, a conducting slide 5 mounted on said base, an adjustable resistance mounted on said base and electrically connected by one of its ends with one of the sets pin-socket and by its other end with said slide, and two conducting wires, one 10 of which is electrically connected to said slide and the other is electrically connected to the other set pin-socket.

2. An electric contact plug comprising an insulating base, two main terminals and two 15 branch terminals carried by said base, said main and branch terminals being respectively adapted to cooperate with the socket and the plug of a usual plug and socket connection and said main terminals being respectively connected with said branch terminals, an insulating block carried by said base, resistance elements supported by said block and connected to one terminal of one 20 of said groups of terminals, a movable slide 25 adapted to contact with said resistance ele-

ments and two conducting wires respectively connected to the other terminal of said group and to said slide.

3. An electric contact plug comprising an insulating base, two main terminals and two 30 branch terminals carried by said base, said main and branch terminals being respectively adapted to cooperate with the socket and the plug of a usual plug and socket connection and said main terminals being respectively connected with said branch terminals, an insulating block carried by said base, resistance elements supported by said block, 35 and connected to one terminal of one of said groups of terminals, a cover for said block, a slot in said cover, a movable slide protruding through said slot and adapted to contact with said resistance elements and two conducting wires respectively connected to the other terminal of said group and to said 40 slide.

In testimony whereof I have signed my name to this specification.

EMILE CHRISTIAN PÉNIN.
